ELECTRON DISCHARGE DEVICE

Paul Haas, Emporium, Pa., assignor to Sylvania
Electric Products, Inc., a corporation of Massa-
chusetts

Application August 22, 1945, Serial No. 612,629

13 Claims. (Cl. 316—19)

1

This invention relates to electron discharge devices of the type having substantially planar parallel electrodes and to a method and apparatus for making an electric device and has more especial reference to the sealing of glass to metal, an object of the invention being an improved sealing of a plurality of metallic parts such as electrodes in the form of discs or rings to a glass envelope portion to provide a composite glass-metal body structure with the metallic parts, spaced in a predetermined manner and to which other metal parts may be attached, subsequent to such sealing.

The terms disc or ring, as used in this case, are merely descriptive to the extent that these electrode parts need not be flat but may be of various shapes, the fundamental requirement being that each has an annular portion equal in outer and inner diameters to those of the glass tubing which forms the envelope, such annular portions conforming to the abutting ends of the tubing which, preferably, are flat. The discs or rings are sealed into the envelope with their axes coincident with and at right angles thereto, their outer peripheries being external of the envelope while adjacent ends of the tubing sections abut and are sealed to the conforming annular portions of the metal.

In electron discharge tubes of the character described and disclosed in my co-pending application S. N. 563,348, filed November 14, 1944, it is often desired to have two electrodes closely and precisely spaced along the axis of the tube, and to have these electrodes of different shapes. The conventional method of assembly has been to make the seals one at a time. First, two sections of tubing are held with adjacent ends against the opposite sides of the flat annular portion of an electrode which latter is then heated through the medium of a surrounding heating element until the glass melts and the seal is made. Then a second electrode and a third section of tubing are sealed to one of the first two-sections of envelope, and so on.

Among the difficulties encountered in this method, particularly when the electrodes are closely spaced, is the problem of relative adjustment of the work and the heating means so that when the second seal is made the other electrode will not absorb enough heat to destroy the first seal. Even when the first seal withstands the reheating it is subject to expansion and distortion, thus limiting the precision of alignment and spacing of the electrodes particularly where high melting point glass or other vitreous material is used. It is therefore difficult to obtain the same characteristics in successive tubes manufactured by this process. Heretofore it has not been pos-

2

sible to make both seals simultaneously because the electrodes, being inherently of different sizes and shapes, absorb the heat at different rates. Thus the electrodes do not reach the sealing temperature at the same time, and the quick-heating electrode cannot be held at the sealing temperature while the other electrode comes up to temperature.

As hereinabove stated a principal object of the invention is to provide an improved method of sealing these disc or ring electrodes whereby two or more electrodes, held precisely in position, are simultaneously sealed into the envelope, thus avoiding the disadvantages resulting from re-heating the completed seals as each successive seal is made.

The invention accomplishes this object by using a method in which each electrode is composed of one or more pieces; the parts, one from each electrode, which are to be sealed to the glass are substantially identical in size and shape or have substantially the same heat absorption characteristics. Another advantage of using rings of substantially the same size is that the seals have approximately the same strain characteristics, thus assuring an hermetic or vacuum-tight seal for all the rings. These similar parts of the electrodes are held, together with the glass tubing, in precise alignment and spacing and the seals made simultaneously, the parts absorbing heat at the same rate. After the seals are completed the remaining parts of the electrodes are fastened by suitable means to the parts which have already been sealed to the glass.

35 The sealed portion of each electrode need consist only of the opposing annular surfaces required for sealing to the adjacent sections of the tubular envelope and whatever additional area is required for attachment thereto of its respective other electrode part or parts. The more complicated parts of the electrodes are made separately. This independence of construction of the electronically active parts of the electrode and the disc or ring members required for sealing has other advantages in addition to allowing more than one seal to be made at the same time.

40 The manufacture of parts is simplified because it is unnecessary to provide an annular sealing surface in the same piece with the more complicated electronically active parts. It is thus also possible to use more complex electrode structures than can be used with electrodes made as units from a single piece of metal.

45 55 The cleaning of the electrodes after sealing is simplified. Since the sealed parts of the electrodes may be small and simply shaped, they do not become so heavily oxidized during sealing,

and their surfaces are more readily accessible for the application of cleaning fluids.

Another object of the invention is the incorporation of a simple way of providing electrical coupling between the electrodes or between resonant cavities which may be associated with the electrodes. The rivets or other devices used to fasten the active parts of one electrode to the sealed disc may be allowed to extend axially down the envelope into proximity with another electrode or through an opening in another electrode into the adjoining cavity.

A further object of the invention is in the fabrication of the discs or rings, to be sealed to the glass tubing, the provision of a series of apertures therethrough whereby such parts cooperate with an assembly fixture as means for holding themselves in true concentricity, and with stop members to limit their movement toward each other to a predetermined and exact parallel spacing as the glass tubing under end pressure becomes shorter during the sealing operation.

And, still another object of the invention is to make further use of certain of the apertures in the said fabricated discs to align the sealed assembly on a second fixture and to employ the others as rivet or screw holes in the fastening of other parts to complete the electrode assemblies.

My invention will be more fully set forth in the following description referring to the accompanying drawing, and the features of novelty which characterize my invention will be pointed out in the claims annexed to and forming a part of this specification.

Figs. 1 and 2 are enlarged end view and elevation, respectively, of the tubular glass sections which form the envelope.

Fig. 3 is a greatly enlarged detail in elevation showing the long and short rivets.

Fig. 4 is a plan view of one of two similar discs used in that embodiment of the invention illustrated in Figs. 9, 10, 11, 11-A, 13, 16, 17, 18, 21 and 24.

Figs. 5 and 6 are detail views in plan and elevation, respectively, of the cup-shaped anode used in both illustrated embodiments of the invention.

Figs. 7 and 8 are views similar to Figs. 5 and 6 of the grid frame.

Fig. 9 is a longitudinal section of the disc assembly after sealing.

Fig. 10 is a view similar to Fig. 9 but showing the cup-shaped anode and the grid frame riveted to their respective discs.

Fig. 11 is a longitudinal sectional view drawn to a still larger scale and illustrating the disc assembly fixture and work pieces thereon before sealing.

Fig. 11-A (Sheet 4) is a view similar to Fig. 11 but drawn to a smaller scale and showing the parts in the relative positions they assume after sealing.

Fig. 12 is a fragmentary view similar to Fig. 11 but with the anode and grid discs shown as formed of thinner metal, the anode disc having a concentric annular, reinforcing depression while the grid disc has both a depressed central portion and a downwardly turned annular flange.

Fig. 13 shows in elevation a sub-assembly of a work piece and fixture part as will be explained.

Fig. 13-A is a top plan view drawn to a smaller scale and illustrative of any suitable removable means for centering the intermediate glass section.

Figs. 14 and 15 are top plan views of the two disc members seen in Fig. 12.

Fig. 16 is a view partly in front elevation and partly in vertical section of the heating apparatus for effecting the disc seal, the work and weights thereon being shown in full lines before sealing and in dotted lines after heat has been applied.

Fig. 17 is a fragmentary view of parts seen in Fig. 16 with the heating coil shown in electrical diagram.

Fig. 18 is a top view of the heating coil with the work positioned therein.

Fig. 19 is a side view of the rack and gear mechanism seen in Fig. 16.

Fig. 20 is a fragmentary detail of the coil supporting member as viewed from the rear with respect to Fig. 16.

Fig. 21 is a view partly in elevation and partly in vertical section of the riveting fixture and the work positioned thereon the grid frame being shown as the part to be riveted.

Figs. 22 and 23 are opposing end views of the movable punch and the fixed rivet holding member, respectively, of the riveting fixture.

And, Figs. 24 and 25 are views in elevation of the completed tubes illustrated in the two embodiments of the invention, part of Fig. 24 being shown in longitudinal central section. In these views the extra anode ring is shown as added which operation is done after sealing.

In the drawing similar reference numerals refer to similar parts throughout the several views.

Referring first to Figs. 1 to 11-A, inclusive, 13, 13-A and 16 to 24, inclusive.

At 1, 2 and 3 are shown the upper, lower and intermediate sections, respectively, of glass tubing which when the electronic tube is completed form the envelope 4, in this instance such sections being of different lengths. Whenever the term "glass" is used it should be understood that any glass like insulating material may be used which is capable of being softened by heat to form a seal with metal.

Spaced apart by the intermediate length of tubing 3 and in abutment with opposing ends of the sections 1 and 2 are two similar discs 5 and 6 through each of which surrounding a central opening 7 are a plurality of holes 6 of one diameter and a like number of holes 9 of a smaller diameter, all arranged with their axes in a circle concentric with the central opening 7. Six of these holes are shown, three of each size, regularly spaced and alternately arranged. The discs, it will be observed, are of greater diameter than the glass tubing to provide an annular exterior portion while there remains between the central opening and the wall of the tubing an exterior portion in which the concentric circle of holes is located and providing a supporting area to which other parts, as will be explained, are attached. The discs 5 and 6, in this modification, are shown as flat although for the purposes of the invention the only flats need be the annular surface portions engaged by the abutting ends of the glass tubing in order that seats be provided for the tubing and whereby the discs are spaced in true parallel relation.

For the purpose of assembling the parts thus far described and as a means for supporting them in assembled relation during the sealing operation, there is mounted upon a suitable pedestal 10, see Fig. 16, shown as of ceramic material, a vertically extending post turned down to provide

a short base 11, a shoulder 12 beyond which is an elongated upper extension 13, and a reduced lower stem 14 which is anchored in the pedestal and threaded to receive a clamping nut 15.

Slidably fitted to the post extension 13 are two similar opposing members 16 and 17 comprising flat rings from each of which extend parallel to the post a plurality of pins 18 and a plurality of tubes 19, the pins of one ring slidably engaging in the tubes of the other, see Figs. 11 and 11-A. These pins and tubes are also regularly spaced and arranged in a circle of like diameter as that in which the holes 8 and 9 are located, the pins also having a sliding fit in the disc holes 9 while the tubes are likewise fitted to the holes 8. An adapter or centralizing sleeve 20 for the tubing 2 is slidably fitted to the base member 11 of the center post. This member, of ceramic material, rests upon the pedestal 10 and is slightly shorter than the height of the shoulder 12. A similar but longer sleeve 21 is slidably fitted to the post extension 13 as a means for centralizing the tubing 1. This adapter sleeve is of a length to extend above the end of post extension 13 but stops short of the upper end of the tubing 1.

Assembly of the parts for sealing and thus providing what is hereinafter termed the composite glass-metal envelope and body structure of the tube, while clearly illustrated in Figs. 11 and 13, will be briefly described as follows:

With adapter sleeve 20 positioned on the base 11 of the center post and resting upon the pedestal 10, the bottom section 2 of glass tubing is placed thereover to also rest upon the pedestal. Ring 17 is then dropped over the post with its pins 18 and tubes 19 extending upwardly and rests upon the shoulder 12. Disc 6 is placed on the tubing 2 and centralized therewith by the pins and tubes 18 and 19 engaging, respectively, through the holes 9 and 8. Next the intermediate tubing section 3 is placed on the disc 6 substantially in alignment with section 2. Preferably the disc 5 is then slipped onto the pins 18 and tubes 19 of the ring 16, as shown in Fig. 13 as a sub-assembly, after which these parts are positioned as shown in Fig. 11 with the disc 5 spaced from disc 6 by the glass tubing 3 and with the pins 18 of one ring slidably engaging a short way into the tubes 19 of the other ring as indicated. The adapter sleeve 21 is then placed over the post extension 13 to rest upon the ring 16 and the tubing section is slipped over such sleeve into abutting engagement with the disc 5.

As a means for precisely centering the intermediate glass section 3 any suitable removable mechanical device may be employed such, for instance, as that illustrated in Fig. 13-A and diagrammatically in Fig. 11. This device, which may be any simple contrivance adaptable for the purpose is shown as a pair of pliers 22 having a pivotal connection at 23 while the nose pieces, when closed upon the work, have a bore 24 the wall of which engages and centralizes the glass tubing 3, the latter being located in relation to the peripheral edge of one of the discs 5 or 6 by engagement therewith of the wall of a concentric counterbore 25 in the centering tool.

A water-cooled high frequency, double wound induction heating coil 26 is shown, with particular reference to Figs. 16, 17 and 18, as horizontally disposed and supported by the terminal extensions 27 and 28 thereof being secured by clips 29 to a plate 30 and having couplings 31 and 32 with a source of water supply and a water out-

let. This plate 30 is laterally adjustable on a bracket 33 slidable on a rod 34 extending vertically from a base 35 which rests upon a table top 36, the bracket being held in any desired position of vertical adjustment by a thumb screw 37.

The pedestal 10 stands upon a block 38 carried by a rack 39 guided for vertical movement through an opening in the table top 36. This rack is operated by a pinion 40 fixed to a shaft 41 mounted in bearings 42 and 43 and rotated by means of a hand wheel 44, a set screw 45 holding the rack in any desired position of adjustment. The electrical connections for the heating coil are illustrated diagrammatically in Fig. 13.

The rack is adjusted to raise or lower the pedestal 10 and thus move the work within the coil so as to bring the discs 5 and 6 into such position that the heating thereof will effect their simultaneous sealing with the glass. A weight is placed upon the upper end of the glass tubing 1 and comprises, in this instance, first a ceramic disc 46 and then the weight proper 47 of suitable heavy metal.

As the glass under heat becomes softened and begins to flow the sections 1, 2 and 3 will become relatively shorter under end pressure of the weight acting against the fixed support. Consequently as the weight drops to the dotted line position indicated in Fig. 16 the discs 5 and 6 will also settle to the dotted line positions indicated in the same figure. In this dotted position the discs will have moved relatively closer together, the final spacing thereof being predetermined by the length of the sleeve 19 which, it will be observed, act as stops by engaging the opposing inner faces of the discs 5 and 6 and at the same time act as leveling means to hold the discs in parallel relation to each other, as is shown in Fig. 11-A.

The seal having been made, weights 46 and 47 are removed and the work disengaged from the fixture. At this time the assembly is as illustrated in Fig. 9 and it will be observed that the surfaces are readily accessible for the application of cleaning fluids.

Further assembly of the tube is as follows:

In the illustrated embodiment of the invention the anode is made of three parts, viz., the disc or ring 5 sealed to the glass tubing sections 1 and 3, a cup-shaped anode proper 48 depending through the central opening 7 and formed with an outwardly turned annular flange 49 having three rivet holes 50 which register with the holes 9 and a like number of outwardly opening radial slots 51 which register with the larger openings 8, and, also, an outer anode ring 52 which is soldered to the disc 5 after sealing.

The grid is made of two parts, viz., the grid disc 6 sealed to the glass tubing sections 2 and 3 and the grid frame the latter comprising an annular ring 53 preferably of like outer diameter as the anode flange 49 with its center opening of like diameter as and registering with the hole 7 in the disc 6. This grid frame or ring carries the grid wires 54 and has a like number of rivet holes 55 and outwardly opening radial slots 56 as there are similar holes 50 and slots 51 in the anode flange 49, the holes 55 registering with the rivet holes 9 and slots 56 registering with the holes 8 in the disc 6.

The fastening devices employed in assembling the parts of the two electrodes are, in this instance, shown as short rivets 57 for the one and long rivets 58 for the other, the heads of the short

and long rivets being provided with reduced pilot extensions 59 and 59^a, respectively, which are coaxial with the shank portions. The short rivets 57 are used for the grid parts while the longer rivets 58 are used for the anode, the extensions 59^a of the long rivets extending into proximity with the grid or, as shown, through the holes 8 in the grid disc, thus providing electrical coupling between the electrodes or between resonant cavities which may be associated with the electrodes.

As shown in Fig. 21, the riveting jig or fixture is of simple construction and includes the two relatively movable members of a punch press. The press member is a post 60 upstanding from a base 61 and having an annular recess adjacent its upper end to provide a head portion 62 and a shoulder 63, the head being drilled to receive three vertically extending sleeves 64 which bottom on the shoulder 63.

As with the assembly fixture hereinabove described, the holes 8 and 9 formed in the disc members 5 and 6 in the fabrication of these parts permit these members to cooperate with the riveting device in centering and properly aligning the work for the riveting operation.

Preferably, the first operation is to attach the grid frame 53. To this end a short rivet is placed on the end of each sleeve 64 where it is held by its pilot 59 extending into the sleeve, as illustrated in Fig. 21. Then with the work inverted so that the tubular section 1 extends downwardly over the post 60 the sleeves 64 registering with the holes 8 in the disc 5 engage through such holes, the disc 6 resting on the rivet heads and the shanks of the rivets passing through the aligned holes 9 and 55 in the disc 6 and grid frame 53.

The punch 65 is recessed to provide a head 66 and shoulder 67 similar to the corresponding parts of the press member. This head 66 is provided, however, with six regularly spaced holes in alternate ones of which are punch rods 68 formed to head the rivets against the grid frame 53 while in the other holes are guide rods 69 which register with and pass through the aligned openings 8 and slots 56 respectively, in the disc 6 and grid frame 53. A spring pressed pressure pad or stripper 70 is carried by the punch to yieldingly engage the work in advance of the punch rods.

To rivet the flange 49 of the anode to the anode disc 5 the operation is the same except that the long rivets 58 are used and the work is reversed so that the tubing section 2 extends downwardly over the part 60. In the final operation the header 71 and exhaust tube 72 are sealed in the usual manner and, with the glass sections 1, 2 and 3, give the complete envelope 4. It may here be stated that sealed into the header 71, previously to its sealing with the tubular section 2, is the cathode sheath 73 which houses the heater-cathode assembly 74, the latter including the cathode grid 75, as shown in Fig. 24.

In some instances, as illustrated in Figs. 12, 14, 15 and 25, the anode and grid discs may be made of much thinner metal, and for the purpose of reinforcing such parts the anode disc 5^a is shown as having an annular depression 76 as the bearing surface for the tubing sections 1 and 3 while the grid disc 6^a is formed with a central depression 77, in which the holes 7, 8 and 9 are located, and a depending annular flange 78 exteriorly of the tubing, the amount of metal in the parts of the two electrodes exteriorly of the glass tubing being substantially the same so as

to allow substantially equal heating. Also, in this modification an outer ring 52^a is soldered to the anode disc 5^a.

While I have shown and described rivets as the means for rigidly securing the parts of the electrodes together it will of course be understood that other suitable fastening devices, as screws, may be used. In this latter event the plunger member of the final assembly fixture would be eliminated.

Furthermore, although I have shown but a single heating unit and manually operable parts associated therewith, it will also be understood that, for quantity production, and without departing from the spirit of the invention a number of the units for the assembly and sealing of the composite glass-metal body structure may be mounted on the intermittently rotatable turret of a machine built for such purpose.

It will also be understood that features of my invention, such as the structural means for facilitating the alignment of the electrode parts may be employed to produce other suitable types of electrical devices.

Although I have shown and described particular embodiments of my invention, I do not desire to be limited to the embodiments described, and I intend in the appended claims to cover all modifications which do not depart from the spirit and scope of my invention.

What I claim is:

1. The method of fabricating a glass to metal article including the steps of assembling a plurality of metal articles having approximately the same heat absorption characteristics with glass members separating the metal articles, simultaneously heating all of said metal articles whereby the glass and metal attains the softening temperature of the glass, while allowing mutual approach between the metallic parts until a predetermined position obtains therebetween, and then stopping relative movement between the metallic parts while allowing the glass to cool and seal with the metallic parts.

2. In the assembly and glass-to-metal sealing of a composite glass-metal body comprising a plurality of metal wafers substantially identical in size and shape and spaced apart in parallel planes by and between sections of glass tubing coaxially aligned therewith, the method of insuring precise, predetermined axial spacing of said wafers, true parallelism thereof and identical sealing-in conditions which comprises the steps of applying heat to produce all seals simultaneously, exerting pressure axially against the end sections of said tubing, guiding said wafers in their relative movement toward each other as the glass tubing shortens under heat and said end pressure, and mechanically arresting such axial movement of said wafers.

3. The method of making a composite glass-metal envelope and electrode body structure for electronic tubes which comprises the steps of arranging a plurality of metal rings coaxially with and as separating means between properly proportioned lengths of glass tubing, exerting end pressure against said tubing, softening the glass adjacent said rings by the application of heat from heating means surrounding said rings, guiding the relative axial movement of said rings toward each other as said tubing sections shorten under heat and said end pressure, and stopping such movement with said rings in parallel relation and at a predetermined spacing, thereby effecting both said predetermined spacing and

a vacuum-tight sealing of the glass to said rings by a single heating operation.

4. The method of making a composite glass-metal envelope and electrode body structure for electronic tubes which comprises the steps of arranging a plurality of metal rings coaxially with and as separating means between properly proportioned lengths of glass tubing, exerting end pressure against said tubing, softening the glass adjacent said rings by the application of heat from a high frequency induction coil surrounding said rings, guiding the relative axial movement of said rings toward each other as said tubing sections shorten under heat and said end pressure, and stopping such movement with said rings in true parallel relation and at a predetermined axial spacing, thereby effecting both said spacing and a vacuum-tight sealing of the glass to said rings by a single heating operation.

5. The method of making an electron discharge tube which includes the steps of vacuum-tight sealing a plurality of planar parallel metal rings coaxially with and to the wall of an open ended cylindrical glass envelope forming tube, said rings being spacers between sections of tubing forming said wall, inserting discharge electrodes into the inner peripheries of said rings, attaching said electrodes to their respective rings, sealing a header, including a sealed-in cathode-heater assembly unit, to one end of said wall, evacuating the tube at its other end, and sealing said evacuation end to completely form said envelope.

6. Apparatus of the character and for the purpose described including a support, a rod upstanding from said support, a shoulder on said rod, an adapter sleeve on said rod below said shoulder, a second adapter sleeve slidable on said rod above said shoulder, two rings slidable on said rod and interposed between said adapter sleeves, the lower ring normally resting upon said shoulder, alternately arranged pins and sleeves parallel to said rod and extending from the opposing faces of said rings, said pins and sleeves being regularly spaced circumferentially and radially with respect to said rod and with the sleeves of one ring telescoping the pins of said other ring, the free ends of said sleeves comprising both a stop for limiting axial movement of said rings toward each other and a support for maintaining said rings in parallel relation when in engagement therewith.

7. The method of making electron discharge devices comprising the steps of forming a pair of annuli with large and small holes, sealing the annuli to axially aligned glass tubes with the small holes on each annulus aligned with the large holes in the other annulus and with one glass tube positioned between the annuli, and securing an electrode to each of said annuli with the aid of pressure applied through the large holes in the opposite annulus.

8. The method of making an electron discharge device comprising the steps of forming a pair of annuli with holes near the central hole of each annulus, sealing the annuli to axially aligned glass tubes while holding the holes of one annulus in predetermined relation to the holes of the other annulus, and with one glass tube positioned between the annuli, and securing an electrode to each of said annuli in predetermined relationship to said holes.

9. The method of making an electron discharge device which comprises simultaneously sealing a number of conductive annuli between sections of

vitreous tubing in accurately controlled axial alignment and mutual spacing, and thereafter securing electrodes to the central apertures of said annuli.

5 10. The method of making an electron discharge device which includes assembling a number of metal rings in alternating order between a number of sections of vitreous tubing, applying axial pressure to said sections of tubing, fusing the edges of said tubing to make joints with said rings, and thereafter securing individual electrode structures to said metal rings.

15 11. Apparatus for assembling plural metal discs to plural glass tubular sections in an alternating succession including a post extending from a base member, a number of spacing sleeves having central apertures slidable over said post and having outer diameters such as to fit within said glass tubular sections whereby said glass sections are maintained in axial alignment and means for limiting the approach of said discs to each other including a number of spacing rings received on said post and interposed between said sleeves.

20 12. Apparatus for assembling plural metal discs to plural glass tubular sections in an alternating succession including a post extending from a base member, a number of spacing sleeves having central apertures slidable over said post and having outer diameters such as to fit within said glass tubular sections whereby said glass sections are maintained in axial alignment and a number of spacing rings received on said post, interposed between said sleeves and each having stop members extending through apertures in said metal discs to engage another metal disc whereby the approach of said discs to each other is limited.

25 13. Apparatus for assembling plural metal discs to plural glass tubular sections in an alternating succession including a post extending from a base member, a number of spacing sleeves having central apertures slidable over said post and having outer diameters such as to fit within said glass tubular sections whereby said glass sections are maintained in axial alignment and a number of spacing rings received on said post, interposed between said sleeves and each having tubular stop members extending through apertures in said metal discs to engage an adjacent metal disc whereby the approach of said discs to each other is limited, each of said spacing rings having an extending pin passing through an aperture in one of said metal discs and received in said tubular stop member to maintain the relative orientation of said discs.
